(57) **CLAIM**

The ornamental design for an aroma device, as shown and described.

DESCRIPTION

FIG. 1 is a perspective view of a first embodiment of an aroma device;

FIG. 2 is a front view of the first embodiment;

FIG. 3 is a left side view of the first embodiment;

FIG. 4 is a rear view of the first embodiment;

FIG. 5 is a right side view of the first embodiment;

FIG. 6 is a top view of the first embodiment; and

FIG. 7 is a bottom view of the first embodiment.

FIG. 8 is an exploded perspective view of a second embodiment of an aroma device;

FIG. 9 is a front view of the second embodiment;

FIG. 10 is a left side view of the second embodiment;

FIG. 11 is a rear view of the second embodiment;

FIG. 12 is a right side view of the second embodiment;

FIG. 13 is a top view of the second embodiment; and,

FIG. 14 is a bottom view of the second embodiment.

The broken lines shown in the figures are for the purpose of illustrating portions of the aroma device and form no part of the claimed design.
